UNITED STATES PATENT OFFICE.

LOUIS E. ENDSLEY, OF PITTSBURGH, PENNSYLVANIA.

DRAFT-GEAR.

1,174,702.

Specification of Letters Patent.

Patented Mar. 7, 1916.

Application filed June 28, 1915. Serial No. 36,722.

To all whom it may concern:

Be it known that I, LOUIS E. ENDSLEY, a citizen of the United States, and resident of Pittsburgh, in the county of Allegheny and State of Pennsylvania, have invented a new and useful Improvement in Draft-Gears; and I do hereby declare the following to be a full, clear, and exact description thereof.

My invention relates to draft gear. Its purpose is to provide for the taking up of severe draft or buffing strains which come upon the cars such as the heavy impact between two cars, as in coupling, and heavy draft strains in long trains. This force is often considerably above the capacity of the present draft gear, which is usually not over 200,000 pounds, while the force, such as the impact force, frequently runs up to a million pounds, and because of the necessity of taking care of it in a short distance, say from 2 to 2½ inches, throws extremely heavy strains upon the underframe, frequently causing the fracture of or other injury to the underframe or draft gear.

In carrying or caring for ordinary strains, however, it is desirable that the travel of the standard draft gear shall not be more than above distance of either two or two and a half inches. By the present invention, I am enabled to take care of the severe or excess strains and relieve the underframe from the same without increasing the normal distance of travel of the standard gear.

To these ends, my invention consists in a compound draft gear formed of a secondary draft gear mounted on the car underframe, and a primary draft gear mounted in said secondary draft gear, such as by a floating gear carrier connected with said secondary draft gear. It also comprises certain other improvements; for example, in the secondary draft gear compressed to sustain approximately the capacity of the primary draft gear, so as to enable the primary draft gear to sustain all ordinary strains and operate as if supported directly in the underframe, while in case of excess strain, the secondary draft gear absorbs and cares for the same. It also includes the employment of spring operated gear in the secondary draft gear to make it practicable to have the same sustain the normal strains upon the primary draft gear.

In the accompanying drawing, Figure 1, is a view of the improved draft gear mount-

ed in the underframe, being shown partly in plan and partly in horizontal section. Fig. 2 is a longitudinal section on the line 2—2, Fig. 1, through the primary draft gear; Fig. 3 is a longitudinal section on the line 3—3, Fig. 1, through the secondary draft gear; Fig. 4 is a front view of the car frame showing the means of supporting the draft gear, the draw bar being shown in section. Fig. 5 is a cross section on the line 5—5, Fig. 1; and Fig. 6 a cross section on the line 6—6, Fig. 1.

My invention may be applied in a variety of ways, the drawing showing one embodiment of the invention, as employed with well known types of draft gear. The underframe 2 has the end sill 3 and bolster 4, the usual center or draft sills 5 being extended toward the end sill, but not reaching to the same, and being connected to the end sills by the top plate 6 of the underframe. Outside of the usual draft sills 5 are supplemental draft sills 7 extending between the bolster and end sill, and the cheek plates 8, 9 are riveted, or otherwise secured to the outer faces of the main draft sills 5 and the inner faces of the supplemental draft sills 7. Mounted in said cheek plates are the secondary draft gears 10, which may be of any spring-operated type of draft gear, those illustrated being known as the Waugh draft gear, which are in part spring and in part friction.

As these draft gears are in normal operation partly compressed, it is believed necessary to use at least partially spring-operated draft gears. These draft gears are connected by yokes 11 with what I have termed the floating gear carrier 12, which I have illustrated as a form of heavy steel casting, which is connected to the secondary draft gears through the yokes 11 by means of keys 13, the draft gears being confined between the follower plates 14, 15. It is to be noted that each such yoke 11 has the cross wall or diaphragm 16 near its forward end, and that the front forward plate 14 is supported against the same. In order to compress each secondary draft gear 10 to the desired capacity for sustaining the primary draft gear 20, the forward follower plate 14 rests against this diaphragm 16, the draft gear is assembled within the yoke, and by pressure against the rear follower plate 15 is compressed to the desired

degree, after which the filler block 17 is inserted between the rear end wall 18 of the yoke, so sustaining such secondary draft gear under high compression. The floating gear carrier 12, having the secondary draft gear 10, is compressed and mounted in its yokes, is sustained in position where two such secondary draft gears are used, between the shoulders 18 of the cheek plates 8 and 9. The floating gear carrier has formed or cast with it the floating cheek plates 21, which extend back between the main draft sills 5 and in which is mounted the primary draft gear 20 which may be of any desired type, the type illustrated in the drawing being the Westinghouse draft gear. This draft gear carries the coupler 22, its coupler shank 23 being connected to the yoke 24 and the draft gear having the follower plates 25, 26, by which it is mounted between the floating cheek plates 21 of the floating gear carrier 12. The primary draft gear is supported in the floating gear carrier by the bearing or cover plate 25 bolted to the gear carrier, and the bearing or cover plate 26 bolted to the main draft sills 8. The entire compound draft gear formed of the gear carrier with its secondary draft gears 10 and its primary draft gear 20 is supported in the underframe by means of the front support or link 28 supported on the end sill 3. There are also the cross supports 29 which are bolted to the main draft sills 5 and to the supplemental or outer draft sills 7 (see Fig. 5), which also prevent spreading of the underframe. These cross supports also carry lugs 32 to sustain the secondary draft gear. The front support or link 28 is shown as connected to the end sill casting 30 riveted to the end sill, and is secured to said end sill casting by means of pins 31 passing horizontally through the front support 28.

In the preferred form of the draft gear, as illustrated, I employ the floating gear carrier, extending across in front of the main draft sills, which are connected to the end sill above the gear carrier, either directly, or through the main cover or floor plating of the car, and locate the secondary draft gear on each side of the main draft sills, while the floating cheek plates of the gear carrier extend between the main sills and receive and support the primary draft gear. As so arranged, assuming that the primary draft gear has a capacity of about 200,000 pounds, the secondary draft gears are compressed to hold about this force—say about 100,000 pounds each—and they thus hold the gear carrier 12 practically without motion, or stationary, until practically the capacity of the primary draft gear is absorbed, permitting it to operate as though mounted directly in the underframe 65 within the distance, say, of two to two and

a half inches. When, however, the force exceeds the capacity of the primary draft gear,—for example, where in draft action, the primary draft gear is closed between the follower plates 25, 26—the draft strain 70 is then transmitted to the secondary draft gears 10, which sustain or absorb the surplus force or excess strain, which may, of course, go up to a half million, or even a million pounds, draft force. In the same 75 way, in sustaining impact strains when the primary draft gear is practically closed, the surplus impact force is transmitted to the secondary draft gears—for example, through the coupler horn 33 contacting 80 with the floating gear carrier 12,—so transmitting the excess impact strains through to the secondary draft gears 10. In such operation, in draft or in impact, the strains are transmitted from the compound draft 85 gear through the cheek plates 8 secured to the main draft sills and the supplemental draft sills, and practically all possible strains are thus transmitted to the underframe while protecting it from injury. 90 This is accomplished in a very small range of movement—say, in ordinary cars, of not more than two to two and a half inches extra movement over that of the primary draft gear. 95

It will be noted that the primary draft gear is illustrated as supported upon a lower level than the secondary draft gear. I prefer this arrangement in order that the coupler horn 33 may be more nearly in line 100 with the secondary draft gears in transmitting the surplus force thereto.

It is to be noted that my invention may be employed in a variety of forms, such as will be understood by the skilled car engineer, and these are intended to be within the scope of the claims.

What I claim is:

1. A compound draft gear formed of a secondary draft gear mounted on the underframe, and a primary draft gear mounted on said secondary draft gear. 110

2. A compound draft gear having a secondary draft gear mounted on the car underframe, a floating gear carrier connected with said secondary draft gear, and a primary draft gear mounted on said floating gear carrier connected with said secondary draft gear, and a primary draft gear mounted on said floating gear carrier. 115

3. A compound draft gear having a primary draft gear and a secondary draft gear said primary draft gear mounted on said secondary draft gear and arranged to receive the main initial draft gear strains. 120

4. A compound draft gear having a secondary draft gear mounted on the underframe and carrying a primary draft gear on said secondary draft gear, the secondary draft gear being compressed to hold without 130

its movement the ordinary strains coming on the primary draft gear.

5. A compound draft gear formed of a spring-operated secondary draft gear 5 mounted on the under-frame, and a primary draft gear mounted on said secondary draft gear, the secondary draft gear being compressed to sustain the main strains coming on the primary draft gear.

10. 6. A compound draft gear having a secondary draft gear mounted on the under-frame, a floating gear carrier forming a part of said secondary draft gear and having floating cheek plates, and a primary 15 draft gear mounted and sustained on said floating cheek plates.

7. A compound draft gear having two secondary draft gears mounted on the under-frame, one on each side of the main draft 20 sills; and a primary draft gear mounted on said secondary draft gear between the main draft sills.

8. A compound draft gear having two secondary draft gears mounted on the 25 underframe on each side of the main draft sills, a floating gear carrier mounted on said two secondary draft gears and having floating cheek plates between said main draft sills, and a primary draft gear 30 mounted on the floating cheek plates of the gear carrier, and sustaining the draft bar.

9. A compound draft gear formed of two secondary draft gears mounted on the underframe—one on each side of the main 35 draft sills—a floating gear carrier connected to said two secondary draft gears and having floating cheek plates between the draft sills, and a primary draft gear mounted on said floating cheek plates and carrying the 40 draft bar, the secondary draft gears being

compressed to sustain the draft upon the primary draft gear.

10. The combination of an underframe having main draft sills and supplemental draft sills outside thereof, each provided 45 with cheek plates, two secondary draft gears mounted on said cheek plates between said main draft sills and said supplemental draft sills; and a primary draft gear carried by said secondary draft gears between the main 50 draft sills.

11. A compound draft gear having a secondary draft gear mounted on the under-frame, a floating gear carrier connected thereto, and a primary draft gear mounted 55 on the floating gear carrier, the yoke of the secondary draft gear being connected to the floating gear carrier and having a cross-diaphragm, the secondary draft gear being spring-operated and compressed against said 60 cross-diaphragm.

12. A compound draft gear having a secondary draft gear mounted on the under-frame, a floating gear carrier connected thereto, and a primary draft gear mounted 65 on the floating gear carrier, the yoke of the secondary draft gear being connected to the floating gear carrier and having a cross-diaphragm, the secondary draft gear being spring-operated and compressed against 70 said cross-diaphragm, and a filler block inserted between the rear end-wall of the yoke and the secondary draft gear to hold the secondary draft gears under compression.

In testimony whereof, I the said Louis E. 75 ENDSLEY, have hereunto set my hand.

LOUIS E. ENDSLEY.
